[57] CLAIM

The ornamental design for a display unit with an attachable camera unit, as shown and described.

DESCRIPTION

FIG. 1 is a top front and right side perspective view of a display unit with an attachable camera unit in the lying posture;

FIG. 2 is a top front and right side perspective view thereof in a standing posture with the camera unit detached and the cord and pen shown in broken lines for illustrative purposes only and forming no part of the claimed design.

FIG. 3 is a top plan view thereof in a lying posture with the camera unit attached;

FIG. 4 is a front elevational view thereof in a lying posture with the camera unit attached;

FIG. 5 is a rear elevational view thereof in a lying posture with the camera unit attached;

FIG. 6 is a bottom plan view thereof in a lying posture with the camera unit attached;

FIG. 7 is a right side elevational view thereof in a lying posture with the camera unit attached;

FIG. 8 is a left side elevational view thereof in a lying posture with the camera unit attached; and,

FIG. 9 is a right side elevational view thereof in a standing posture with the camera unit attached.
